WEB SEVERING MECHANISM

Arthur Bell, London, England, assignor to American Machine & Foundry Company, New York, N. Y., a corporation of New Jersey

Application August 20, 1938, Serial No. 225,975
In Great Britain September 28, 1937

6 Claims. (Cl. 164—47)

This invention relates to web severing mechanism of the type in which sections of material such as cork in connection with the cork tipping of cigarettes are severed from a moving web of the material.

It is found desirable in connection with the cork and like tipping to so arrange the angle of cut, which would normally be at right angles to the direction of feed of the web, that the cut edges of the section lie oblique to the length of the section, and it is an object of the present invention to provide an improved mode of mounting the knives so that an alteration in the angle of cut may be readily effected.

According to the invention a mounting for the co-operating knives is provided which is capable of oscillation about a transverse axis, means being provided whereby the angle of the mounting may be adjusted relatively to said axis by a rotational movement about the longitudinal axis of the mounting.

The oscillatory movement of the mounting may be effected by a crank device the pin of which engages the mounting through a self-aligning ball bearing.

Further features of the invention will be hereinafter described and defined in the claims.

In the accompanying drawings which illustrate a mounting according to the invention;

Figure 1 is a side view and

Figure 2 is an end view.

Figure 3 is a partial section showing a modified form of knife.

In carrying the invention into effect as applied by way of example to the severing of sections from a moving web of tipping material, a knife mounting is provided which is composed of upper and lower parts 5 and 6 by which the upper and lower co-operating knives 7 and 8 are respectively carried. The lower part 6 of the mounting is adjustably secured upon a saddle piece 9 which is pivoted upon a relatively fixed spindle 10 about an axis parallel to the plane of the knives. The adjustment between the lower part 6 and the saddle 9 permits of a rotational movement of the mounting about its longitudinal axis which is located in the cutting plane of the knives and passes through the pivotal axis of the saddle piece.

The lower part 6 is provided with a cross piece 11 which seats upon a surface 12 of the saddle piece which is at right angles to the longitudinal axis of the mounting. The cross piece is provided with a circular projection or spigot 13 coaxial with said longitudinal axis and engaging

in a complementary recess 14 in the seating surface of the saddle.

The saddle is provided at one side with spaced upwardly extending lugs 15 which accommodate adjusting screws 16 lying parallel to the seating surface. The screws 16 engage the side surface or edge 17 of the cross piece whereby the mounting may be pivotally adjusted about the axis of the spigot, i. e., the longitudinal axis of the mounting.

The surface 17 of the cross piece engaged by the adjusting screws is inclined so that the screw will press the cross piece on to the seating.

A locking screw 18 is provided adjacent the opposite edge of the saddle. This screw is arranged parallel to the longitudinal axis and extends through an enlarged hole 19 in a flange 20 on the saddle piece, the clearance of the hole being sufficient to allow for the maximum adjustment of the mounting required.

The spindle 10 is secured upon a shaft 21, the axes thereof being eccentric, whereby adjustment of the lower part of the mounting may be effected.

The upper part 5 of the mounting is adapted for movement towards and away from the lower part 6 in order to obtain a cutting stroke of the knives.

This movement is preferably obtained by the provision of a telescopic coupling between the parts. Thus the upper part is provided with spaced downwardly extending rods 22 which slide in complementary sockets 23 on the lower part.

The reciprocatory movements of the upper part 5 are obtained by a crank device 24 the crank pin 25 of which engages in the inner race of a self-aligning ball bearing 26 carried in an end recess 27 in the upper part. By this arrangement any oblique setting of the mounting will be automatically accommodated by the self-aligning ball bearing.

The crank device also imparts an oscillatory movement to the mounting about the spindle 10, producing a movement at the plane of cut corresponding to the length of the sections being severed from the web.

The crank pin 25 may be radially adjustable for varying the length of cut.

In order to adjust the mounting for producing an oblique cut, the locking bolt 18 is slackened, whereupon the mounting may be pivoted around the spigot 13 to the desired angle by adjusting the screws 16. After adjustment the locking bolt is again tightened.

The co-operating knives are mounted upon the

upper and lower parts in any suitable manner so that they may be adjusted to the desired position, it being observed that the plane of the cut coincides with the longitudinal axis of the mounting while the knives are so mounted that the medial line thereof also coincides with said axis.

Thus according to the form shown in Figures 1 and 2 in which the knives are formed of a substantial thickness the upper knife 7 is secured by screws 28 and abuts against adjusting screws 29. The lower knife 8 is secured by locking screws 30 and bears against adjusting screws 37. The lower knife 8 is formed as a slotted plate against which the upper knife 7 is always in contact.

A web guide 32 is secured to the lower mounting 6 and comprises a thin plate bent up to provide a flared opening which seats adjacent the slot of the knife 8.

20 According to an alternative arrangement (see Figure 3) the knives 7a and 8a are mounted upon spring strips 34 and 35, the strips being secured by the locking cap screws 28, 30 and adjusting screws 29 and 31.

25 The lower knife 8a is provided with side horns 36 against which the knife 7a is guided.

I claim:

1. A mounting for the co-operating knives of a web severing mechanism, comprising upper and lower parts carrying co-operating knife elements and movable relatively to one another longitudinally of the mounting, a fixed supporting spindle transfixing said lower part and around which said mounting can be swung bodily to shift the shearing line selectively forward and backward relatively to the length of the web, a pivotal connection between said lower mounting part and said transverse spindle to permit rotative adjustment bodily of the mounting around its longitudinal axis perpendicular to the axis of said spindle, to set the line of shear of the knives obliquely to the direction of web-feed, and means to cause relative shearing movement as between said knives, by relative reciprocation between said 45 knife-carrying parts, in the various positions of said swinging and rotative adjustment of said mounting relatively to said web.

2. A mounting for the co-operating knives of a web severing mechanism, comprising upper and lower parts having a telescopic connection whereby they are movable relatively to one another longitudinally of the mounting, a saddle piece pivotally mounted on an axis transverse to the mounting, said saddle piece having a recess, a spigot on said lower part engaging the recess, the axis of the spigot coinciding with the longitudinal axis of the mounting and intersecting the pivot axis of the saddle piece, a self-aligning bearing carried by the upper part, and a crank

device the pin of which engages the self-aligning bearing.

3. A web-severing mechanism comprising a mounting including parts movable relatively to each other and carrying knife elements cooperating by reason of said relative movement to operate upon a web fed therebetween, a supporting structure upon which one of said parts is journaled to permit oscillation of said mounting swingingly around the axis of said journal, a pivot connection between contiguous parts of said supporting structure and mounting and means whereby said mounting is adapted to be adjusted rotatively around an axis approximately perpendicular to the shear line of said knives, and a crank device including a crank pin, and also including a self-aligning ball-bearing carried by the other part of said mounting, whereby said oscillation of the mounting swingingly around the axis of said journal support, and consequent relative cooperative movement of said knife elements, is effected when said crank device is actuated, regardless of the relative adjustive positions occupied by said parts.

4. A web-severing mechanism having the features claimed in claim 3, wherein provision is made of a saddle piece, having a recess, a spindle upon which said saddle piece is mounted pivotally and a spigot on the mounting engaging in said recess, the axis of said spigot coinciding with the longitudinal axis of the mounting and intersecting the axis of the spindle.

5. A web-severing mechanism having the features claimed in claim 3, wherein provision is made of upper and lower parts movable relatively to one another longitudinally of said mounting, said lower part having a spigot; a spindle; and a saddle piece mounted pivotally upon said spindle and having a recess in which said spigot engages, the axis of the spigot coinciding with the longitudinal axis of the mounting and intersecting the axis of the spindle.

6. A web-severing mechanism having the features claimed in claim 3, wherein provision is made of upper and lower parts movable relatively to one another longitudinal of the mounting, a double pivotal support for said lower part whereby the mounting is swingable both about a transverse axis, and about a longitudinal axis, co-operating knives carried by said upper and lower parts, one of said knives comprising a plate having a body slot over the edge of which the other knife slides, co-acting with said edge of the slot to sever the web passing through the slot, means to direct the web into said slot, and means to direct therefrom the severed parts of the web as they emerge from the slot.

ARTHUR BELL.
